UNITED STATES PATENT OFFICE.

WALTER ROGERS BENJAMIN, OF CHINOOK, MONTANA.

CLAW-HAMMER.

1,287,619.

Specification of Letters Patent. Patented Dec. 17, 1918.

Application filed May 7, 1918. Serial No. 233,006.

To all whom it may concern:

Be it known that I, WALTER R. BENJAMIN, a citizen of the United States, residing at Chinook, in the county of Blaine and 5 State of Montana, have invented a new and useful Claw-Hammer, of which the following is a specification.

This invention relates to hammers and more particularly to that class known as 10 claw hammers.

The object is to provide such a hammer with means for connecting the claws at an intermediate point thereof to the hammer handle adjacent to the hammer head, where- 15 by great power may be exerted in drawing nails or the like, without the danger of breaking the said claws or handle during such operation.

Another object is to provide means for 20 bracing the claws and handle as above stated, and at the same time permit of the necessary resiliency in the handle which eliminates the stinging of the hand of the operator when using the hammer, and to so 25 arrange the said connecting means as to engage the handle and brace the same without the necessity of using screws or other fastening means.

A full and complete understanding of the 30 invention may be obtained from a consideration of the following detailed description, taken in connection with the accompanying drawing forming a part of this specification; it being understood that, while the 35 drawing shows a practical form of the invention, the latter is not confined to strict conformity therewith, but may be changed or modified, so long as such changes or modifications mark no material departure 40 from the salient features of the invention, as specifically pointed out in the appended claims.

In the drawing in which like reference 45 characters designate corresponding parts throughout the several figures:—

Figure 1 is a perspective view of a hammer embodying the improvements of the present invention.

Fig. 2 is a sectional view, taken on the 50 line 2—2 of Fig. 1 and looking in the direction of the arrow.

In using the ordinary claw hammer to draw nails or the like in the well-known manner, it often happens, when undue power

is exerted upon the handle thereof in an upward direction, that, by reason of the frictional engagement of the nail in its seat, the handle of the hammer is broken off near the hammer, due to the great leverage provided by the length of the handle and the claws 60 and their relative distances from the fulcrum of the hammer head.

To obviate the possibility of thus breaking the said hammer handle and to further strengthen the claws by connecting the two, 65 without, in any way interfering with the desired resiliency of the handle, which should not be bound or secured at any point outside of its point of entrance into the hammer head, the following means are employed and 70 have been found to accomplish the desired results very effectually.

The hammer head 1, having the usual nose 2 and claws 3, is provided with the handle socket 4, at the proper intermediate point between the nose and claws to secure the proper balancing thereof when applied to the handle 5 in an ordinary manner.

By reason of the improved bracing or strengthening means about to be described, 80 the customary tapered walls forming an extension of the socket and embracing the end of the handle where entering the head, are dispensed with, thus effecting a material saving in the cost of manufacture of hammers, as the above extension of the socket 85 has been found to be expensive to produce.

At an intermediate point of the length of the claws 3, a metallic, substantially V-shaped loop 6 is provided, extending toward 90 and embracing the handle 5 and having its terminals secured to the claws as by electrically welding or otherwise permanently securing the same. The spaced arms 7 of the loop 6 are preferably flat, relatively 95 thin, arcuately curved members, placed edge-wise of the longitudinal axis of the hammer handle 5, and having their concaved edges directed toward the head of the hammer, as clearly illustrated in Fig. 1 of the 100 drawing. The end of the loop 6, or connecting part or bridge between the arms, as indicated at 8, is bent to closely fit the handle, the sides of the loop embracing the sides of said handle at a point adjacent to the 105 head. The claws, in the present instance, may be somewhat lengthened in order to facilitate their use in prying up boards or the

like, without the danger of breaking the same, by reason of the herein described bracing and strengthening means.

By reason of the fact that the combined width of the claws is somewhat greater than the thickness of the handle, the arms 7 diverge at their outer ends, where connected to said claws, as seen by reference to Fig. 2, and their outer faces lie flush with the outer sides of the claws, the inner faces of the arms being increased in thickness and rounded where connected to the claws, as shown at 9, in order to lend great strength to the point of juncture with said claws.

From the foregoing it will be seen that simple means have been provided for connecting the claws of a hammer to the handle thereof, which will effectually brace the same and aid materially in preventing breaking the handle when excessive power is applied in drawing out nails or the like. The arms 7 do not interfere in the slightest in applying the claws to the head of a nail, no matter what size the latter may be, as there is ample room between the claws and the bracing arms for the passage of the same. Furthermore the claws extend beyond the terminals of the arms 7, where connected to the former, sufficiently to be advantageously used in prying up boards and for other kindred uses. The additional cost of providing a hammer with the herein described improved strengthening means is balanced by the elimination of the extended socket referred to, so that the hammer may be manufactured at a reasonable cost.

The arms 7 further render the hammer capable of being hung upon a nail without turning thereon and dropping off as is the case with most hammers not provided with the device. It will be observed that the bracing loop does not obstruct the nail re-

ceiving slot or space separating the claws, and the same free use of the claws is permitted as with an ordinary claw hammer.

45

What is claimed is:—

1. A claw hammer comprising a hammer head, claws, and a handle, a substantially V-shaped loop consisting of arms integrally connected to the claws at an intermediate point of their lengths, and a bridge connecting the ends of the arms and bearing against the handle, the sides of the loop fitting closely the sides of said handle, whereby the claws and handle are mutually braced, the space between the claws being unobstructed throughout, whereby free use of the claws is permitted.

50

2. A claw hammer comprising a hammer head, claws, and a handle, spaced, arcuately-disposed flat-faced arms rising from the hammer claws at an intermediate point of their lengths toward the said handle and set edgewise to the longitudinal axis of the handle, the outer faces of said arms being flush with the side faces of the claws, the inner faces of the arms gradually swelling and merging into the claws, the said arms being connected at their other ends by an end portion adapted to bear against the handle on the edge opposite to the claws for bracing the handle when the claws are in operation, the space between the claws for the engagement of a nail being unobstructed throughout, and the claws extending beyond the said arms a material distance so as to permit of their free use.

55

In testimony, that I claim the foregoing as my own, I have hereto affixed my signature in the presence of two witnesses.

WALTER ROGERS BENJAMIN.
